[57] CLAIM

The ornamental design for a triple dresser with mirror, as shown and described.

DESCRIPTION

FIG. 1 is a perspective view of a triple dresser with mirror showing our new design;

FIG. 2 is a left side elevational view thereof, the right side being a mirror image thereof;

FIG. 3 is a front elevational view thereof; and,

FIG. 4 is a top plan view thereof.

The rear and bottom of the dresser are unornamented.
